(57) **CLAIM**

The ornamental design for an insert for a box, as shown and described.

DESCRIPTION

FIG. 1 is a front perspective view of the insert for a box; FIG. 2 is a rear perspective view of the invention with an upper portion folded over;

FIG. 3 is a front elevation view of the invention;

FIG. 4 is a rear elevation view of the invention;

FIG. 5 is a top plan view of the invention;

FIG. 6 is a bottom plan view of the invention;

FIG. 7 is a left side view of the invention; and,

FIG. 8 is a top plan view of the invention with entire insert disassembled and lying flat.

In FIG. 8, the broken lines represent fold lines, which form part of the claim.
